O. FESSLER,
BRACELET LINK.
APPLICATION FILED APR. 4, 1919.

Patented July 11, 1922.

WITNESS:

INVENTOR:

BY

UNITED STATES PATENT OFFICE.

OTTO FESSLER, OF IRVINGTON, NEW JERSEY.

BRACELET LINK.

1,422,428.

Specification of Letters Patent.

Patented July 11, 1922.

Application filed April 4, 1919. Serial No. 287,460.

To all whom it may concern:

Be it known that I, OTTO FESSLER, a citizen of the United States, and a resident of Irvington, in the county of Essex and State 5 of New Jersey, have invented new and useful Improvements in Bracelet Links, of which the following is a specification.

This invention relates to links comprising opposite connected side parts, called the 10 "bean," and a middle part which may or may not be longitudinally slideable with respect to the side parts, the construction being one that is frequently employed in extension bracelets or bracelets in which the 15 links can stretch.

The objects of the invention are to secure a smooth continuous exterior surface of the middle part or strip of the link, flush with the opposite side parts; to thus secure a 20 neat and pleasing appearance, and at the same time secure a proper working relation between said parts; to do this by swaging out of the middle part of the link edge lugs or ears which shall project into the opposite 25 side parts of the link; to form such lugs or ears without impairing the outer surface of the middle part of the link; to so arrange such ears or lugs along the blank for said 30 middle part of the link that the middle part when formed will be either fast or slideable 35 with respect to the rest of the link, as desired; to thus enable the same blank to be employed for the two different kinds of links; to thus secure economy and convenience, and to obtain other advantages and 40 results as may be brought out in the following description.

Referring to the accompanying drawing, in which like numerals of reference indicate 45 the same parts throughout the several views.

Figure 1 is a plan of the outer side surface of the blank for the middle part of a link of my improved construction;

Figure 2 is a view of the inner side surface; 50

Figure 3 is an edge view of the blank;

Figure 4 is a plan of a complete link;

Figure 5 is a cross-section on line 5-5, Fig. 4;

Figure 6 is a longitudinal section on line 6-6, Fig. 4, showing the middle part of the link in edge view, and

Figure 7 is a similar longitudinal section of a link with the middle part fixed.

55 In the specific embodiment of the inven-

tion shown in said drawings, 1, 1 indicate the side parts of the link stamped out of sheet metal each in dished form as shown in Figure 5, and having at one end an integral connection 2 while at the other end 60 they are connected by engaging members 3, 4.

Between said side parts 1, 1 is arranged the middle part 5 (or 15) of the link, which is bent up out of a sheet metal strip or blank 65 6 shown in Figures 1, 2 and 3. This blank has one of its side surfaces smooth or continuous, but out of the other side surface projection or ears are formed by swaging which projects beyond the edge of the main 70 portion 7 of the strip, said main portion being just wide enough to slidably fit between the side parts 1, 1 of the link. Figures 3 and 2 show in edge view and looking at the surface of the blank which is inside 75 the middle part of the link, how the ears are stamped or swaged out, and it will be seen that there are two pairs of ears, 8, 8 and 9, 9, spaced along the length of the blank.

These ears when the blank is bent into 80 the finished middle part project into the dished side parts 1, 1 and retain said middle part against displacement laterally from between the side parts 1, 1, it being understood that the outer surface of the closed 85 side of the middle part lies flush with the side parts 1, 1. At the other side of the middle part one of the ends of the strip or blank 6 from which it is formed is bent into a resilient tongue 10 (or 13) and the other 90 end is bent into a keeper 11 (or 14) against which the tongue 10 normally lies and yet can be displaced inward therefrom so that a snap hook is provided.

The two sets of ears 8, 8 and 9, 9 are so 95 spaced with respect to each other and with respect to the length of the blank 6 that if the end of the blank next the longer ears 8, 8 is formed into the keeper 11 and the other end into the tongue 10, the long lugs 8, 8 lie 100 at the closed side of the middle part 5, as shown in Figure 6, and the short ears 9, 9 lie at the opposite side. Under these circumstances the middle part 5 can slide with respect to the rest of the link, and if a spring 105 12 is inserted as is common in the art an extension link is provided. On the other hand, if the end of the blank 6 next the long lugs 8, 8 is formed into a tongue 13 and the opposite end into a keeper 14, as shown in 110

Figure 7, the short ears 9, 9 abut against one end of the body part of the link and the long ears 8, 8 extend around the curved opposite end of the middle part of the link and 5 bear against the portion of the next link, (not shown), which passes through the link described, so that there can be no sliding motion of the middle part 15 of the link. This forms what is called a "dead" link, or 10 one having its middle part fixed or stationary with respect to the side parts, while the link shown in Figure 6 is what is known as a "live" link, and it is a feature of my invention that the same blank can be employed for forming both kinds of links.

Whichever kind of middle part of a link is made from my blank, however, the ears 8, 8 and 9, 9 project beneath the edges of the dished side portions 1, 1 and hold the middle 20 part firmly and accurately in position with its smooth continuous outer surface flush with the edges of the side parts 1, 1, so that a link of high finish and artistic appearance is secured. While I have shown my improved construction applied to a particular kind of links, obviously the invention can be utilized for any purpose to which it is adapted and I do not wish to be understood as restricting myself except as required by 25 the following claims when construed in the light of the prior art.

Having thus described the invention, what I claim is.

1. In a link of the character described, 35 the combination with opposite side parts having their adjacent faces recessed, of a middle part between said side parts in the form of a looped strip having at its lateral edges ears offset inwardly from that portion 40 of its outer surface between said ears and projecting into the recesses of said side parts to hold the middle part against displacement from between the side parts.

2. In a link of the character described, 45 the combination with opposite side parts having their adjacent faces recessed, of a middle part between said side parts in the form of a looped strip having at its lateral edges ears offset inwardly from that portion 50 of its outer surface between said ears, said ears projecting into the recesses of said side parts to hold the middle part against displacement from between the side parts, and said portion of the outer surface of the 55 middle part between said ears being continuous and flush with the adjacent portions of its outer surface.

3. In a link of the character described, 60 the combination with opposite side parts having their adjacent faces recessed, of a middle part between said side parts in the form of a looped strip having at its lateral edges ears offset inwardly from that portion of its outer surface between said ears,

said ears projecting into the recesses of 65 said side parts to hold the middle part against displacement from between the side parts, and said portion of the outer surface of the middle part between said ears being substantially flush with the edges of the side 70 parts.

4. The method of forming either a slide- 75 able middle part or a fixed middle part for links of the character described from a strip having at its edge a lateral projection adapted to extend into the recess of one of the side parts of the link, which method consists in making the keeper from that portion of the strip at one side of said projection to produce a middle part of one of said 80 kinds and making the keeper from that portion of the strip at the other side of said projection to produce a middle part of the other kind.

5. A middle part for links of the char- 85 acter described, comprising a looped strip having at spaced points of its length projections from its lateral edges offset in the direction of the thickness of the strip inwardly from its outer surface and adapted to ex- 90 tend into the recesses of the side parts of the link to prevent edgewise displacement of the middle part from between the side parts in either direction.

6. A middle part for links of the char- 95 acter described, comprising a looped strip having at spaced points of its length integral ears at its lateral edges offset in the direction of the thickness of the strip inwardly from its outer surface and adapted to ex- 100 tend into the recesses of the side parts of the link to prevent edgewise displacement of the middle part from between the side parts in either direction.

7. A middle part for links of the char- 105 acter described, comprising a looped strip having a lateral projection at one of its edges offset inwardly from that portion of the outer surface of the strip which is in alignment with said projection transversely 110 of the strip, said projection adapted to extend into the recess of one of the side parts of the link and hold the middle part against displacement.

8. A middle part for links of the char- 115 acter described, comprising a looped strip having its opposite longitudinal portions each provided with a lateral projection adapted to extend into the recesses of the side parts of the link and hold the middle 120 part against displacement, said projections being offset inwardly from the outer surface of the middle part.

9. A blank for a middle part for links of the character described, comprising a strip 125 having at spaced points of its length lateral edge projections for extending into the recess of the side parts of the link and hold-

ing the middle part against displacement, said projections being offset from both sides of the strip.

10. A blank for a middle part for links of the character described, comprising a strip having at spaced points of its length integral ears projecting from the edge of the strip and adapted to extend into the recess of the side parts of the link and hold the middle

10 part against displacement, said ears being offset from both sides of the strip.

11. A blank for a middle part for links of the character described comprising a strip having at spaced points of its length 15 pairs of opposite lateral projections for extending into the recesses of the side parts of the link and holding the middle part

against displacement, said projections being offset inwardly from both sides of the strip.

12. A blank for a middle part for links 20 of the character described, comprising a strip having at one of its edges a lateral projection offset inwardly from both sides of the strip and adapted to extend into a recess of the side parts of the link to position the 25 middle part with respect thereto.

13. A blank for a middle part for links of the character described, comprising a strip having at one of its edges an integral ear offset inwardly from both sides of the 30 strip and adapted to extend into a recess of the side parts of the link to position the middle part with respect thereto.

OTTO FESSLER.
